UNITED STATES PATENT OFFICE.

RAYMOND C. PIERCE, OF ST. LOUIS, MISSOURI.

ALARM OF VARIABLE INTENSITY.

Continuation of application Serial No. 503,780, filed September 28, 1921. This application filed July 28, 1922. Serial No. 578,058.

This invention relates to an improvement in alarm clocks and particularly to an alarm clock in which the intensity of the alarm is progressively increased from a mere buzz to an alarm of full intensity. The present application is a continuation of my application 503,780 filed September 28, 1921. This increase may be by one cycle or by a succession of cycles, the alarm dropping back to low intensity from high. A further object is the provision of an alarm of progressively increasing intensity in which the initial intensity of the cycle may be varied and in which the variable feature may at will be entirely dispensed with. A further object is the provision of an intermittent alarm which may, as desired, be operated either with or without the variable feature, or be omitted. Further objects will appear from time to time in the course of the specification.

I illustrate my invention more or less diagrammatically in the following drawings, wherein:

Figure 1 is a rear view looking towards the face of the clock with the back plate broken away.

Figure 2 is a view similar to Fig. 1, with parts omitted.

Figure 3 is a section along the line 3—3 of Fig. 2.

Figure 4 is a section on the lines 4—4 of Fig. 3.

Fig. 5 is a section on the lines 5—5 of Fig. 4.

Figure 6 is a section on the lines 6—6 of Fig. 4.

Figure 7 is a section on the lines 7—7 of Fig. 5.

Figure 8 is a section on the lines 8—8 of Fig. 6.

Like parts are illustrated by like letters and numbers throughout the drawings.

A, Fig. 1, is a main spring, diagrammatically illustrated, which drives the main spring wheel A¹ which drives the central wheel A² and actuates the center shaft A³ to which the minute hand A⁴, Fig. 3, is attached. The center wheel A² connects through the wheels A⁵ and A⁶ to the escapement wheel A⁷ and the balance wheel A⁸. The hour hand A⁹ is actuated through a pinion A¹⁰ which is secured to the central shaft A³, and meshes with the wheel A¹¹, the pinion A¹² rigid therewith, which meshes with the wheel A¹³ which is

loose on the shaft A³ to which the pinion A¹⁰ is secured. The hour hand A⁹ is attached to the hub of the wheel A¹³ and turns with it.

An alarm spring beneath the plate B drives the alarm spring wheel B¹ Fig. 1 and through it the pinion B², the wheel B³, the pinion B⁴ and the alarm escapement wheel B⁵. The latter actuates the escapement lever B⁶ which is keyed to the shaft B⁷ and oscillates it.

Keyed also to the shaft B⁷ and oscillating with it and the lever B⁶ is a curved oscillating lever arm C, slotted as at C¹⁰, which drives the alarm hammer C⁸ through the levers C², C³, C⁴, and C⁵ which are pivoted to each other and properly secured to the frame of the clock. On the end of the lever C² is a pin C¹⁶ which passes through the slot C¹⁰ and is slideable therealong forming the driving connection between the lever C and the lever C².

Pivoted on the center shaft A³ is the guide rod D slotted as at D¹⁵, which slotted end engages the link C and is also traversed by the pin C¹⁶, which thus rides both in the slots C¹⁰ and D¹⁵. Connected to the guide rod D and on the opposite side of the pivot point is a short lever arm D² against which bears the guide rod spring D¹ which tends to force the slotted end of the guide rod in the direction of the shaft B⁷. Midway on the rod D is the pin D⁴ which is yieldingly pressed by said spring D¹ against the spiral cam surface D⁵ which is driven from the cam wheel D⁵ Fig. 75

1 acting through the pawl D⁶ which is attached to said wheel and the ratchet wheel D⁷ which is keyed to the shaft D⁸ on which the cam D⁸ is also keyed. The spring D⁹ holds 80 the pawl D⁶ to the ratchet wheel D⁷. The cam wheel D⁵ turns on the shaft D⁸, being held in place on the shaft by the cam D⁸ and the cam ratchet wheel D⁷, see Fig. 3. The cam wheel D⁵ is actuated by the pinion D¹⁰ 85 which is rigidly connected to the pinion D¹¹, both working loosely about the shaft D¹². D¹⁰ is therefore actuated by the pinion D¹¹ and in turn through it by the alarm spring wheel B¹. 90

The shaft D⁸ terminates outside of the frame in the thumb screw E through which the cam D⁸ may be set to position to give minimum initial intensity of alarm, or to any other position. The various positions may 105 be indicated by suitable markings on the outside of the case. The thumb screw E and the cam D⁸ can be turned only counterclockwise

as seen in Fig. 1, this being the normal direction of rotation.

The position of the guide rod D along the link C is adjusted by means of the sliding control sector F with the ear F¹ against which the end of the rod D is yieldingly pressed through the spring D¹ and the lever D². The ear F¹ limits the movement of the rod D in the direction of the shaft B⁷ while the slot C¹⁰ 10 and the pin C¹⁶ on the lever c² limits its travel in the opposite direction, or in other words the rod D thereby controls the lever C². The adjustment is made by pushing the sliding control indicator F², the travel of which is 15 limited by the pin F³ mounted in the sliding control sector F, which moves in the slot F⁴ in the plate F⁵ which holds the sector F against the frame element F⁶.

G is an intermittent lever pivoted on the 20 shaft G¹ and actuated by the wheel A²⁰ which is rigidly attached to the shaft A²¹ and is toothed to engage the stop G² on the short lever arm G³ which is integral with the lever G. The spring G⁸ tends yieldingly to press 25 the lever arm G³ against the wheel A²⁰. The teeth of the wheel A²⁰ are inclined and as it rotates they lift the stop G² and thus oscillate the lever G. At the outer end of the lever G are the two stops G²⁰ and G²⁵, the first of 30 which, when the stop G² is in the position nearest the center of the wheel A²⁰, and the lever G is accordingly in its position nearest the shaft B⁷, engages the triangular stop G⁶ which is set in the end of the arm C¹⁵ 35 which is a continuation of the slotted link C. In such position the lever G and the stop G²⁰ prevent the oscillating lever arm C from moving. This position of the lever G is shown in dotted lines in Fig. 2. As the wheel 40 A²⁰ continues its rotation, the stop G² is raised, and moves the lever G to the position shown in the full lines, releasing the stop G⁶ and the lever arm C.

The sliding sector G⁴ and the sliding control indicator G⁵ may be moved to hold the lever G in an inoperative position, the pin G⁷ on the sector G⁴ engaging the end of the lever G as in Fig. 1.

The alarm is set by the alarm cam H which 50 is keyed to the shaft H¹ on which, located on the outside of the case, is a lever H² Fig. 6. The cam H is shown in Fig. 1 as in an inoperative position. When the lever is turned about 180°, the cam H will engage the end 55 of the oscillating lever arm C¹⁵, and will thus prevent oscillation of the lever C.

The release cam H⁴ Figs. 4 and 6 is rigidly attached to the wheel H⁵, both working loosely on the shaft D¹². The wheel H⁵ is actuated by the pinion A¹², the wheel A¹¹ and the pinion A¹⁰ which are all driven from the center shaft A³. The spring H⁷, when the release cam H⁴ turns to the time set for release, as indicated by the alarm hand H⁶, 60 presses the release wheel H⁵ down over the

ear H⁸. The stop H³, which is shown as integral with the spring H⁷ drops with it and releases the lever arm C¹⁵ and thus the lever C.

While I have illustrated a practical device, I wish the drawings and description to be taken as in a large sense diagrammatic. It is obvious that many changes might be made in the number, shape, and relation of parts, without departing from the spirit of 75 my invention.

The use and operation of the invention is as follows:

I have illustrated an alarm clock in which the main spring drives the hour and minute 80 hands in the usual manner. The alarm spring drives the alarm hammer through a series of levers as illustrated. In order to provide an alarm of varying intensity, I control the hammer blows on the bell by means 85 of a progressively varied lever action. The initial lever C is curved and slotted and in this curved slot fits the pin C¹⁰ on the end of the lever C², permitting a variable point of engagement between the two levers. As the 90 lever C vibrates with the shaft B⁷, the nearer the end of the lever C² is to that shaft, the smaller will be the throw given to the hammer. When the end is in the point nearest 95 said shaft, the motion transmitted to the chain of levers is so small as to be taken up along their various pivotal connections, leaving the hammer C⁶ in contact with the bell, or if desired, giving it a very slight reciprocation to cause a mere buzz. The progressive 100 increase of the alarm is provided by moving the end of the lever C² outwardly from the shaft B⁷ to the outer end of the lever C, the length of the stroke of the hammer C⁶ being thereby gradually increased. 105

It is observed that an important feature of applicant's embodiment of his invention has been the proportion of the two curved slotted links in such wise that their adjustment for motion in relation to each other would vary the length of the travel or reciprocation of the pin C¹⁶ along the slot D¹⁵ without cramping or jamming the pin. It will be understood that the pin C¹⁶ is rigidly secured to the lever C² and traverses or rides along the slot D¹⁵ and the slot C¹⁰. The desired result is obtained as follows:

The point B⁷ is the axis of the shaft about which oscillates the curved and slotted lever arm C, both being shown in Fig. 1. The shaft A³ is the pivot about which the slotted guide rod D of Fig. 1 rotates. For the purpose of making the outer end of the guide rod swing concentrically with the ear F¹ of the sliding control sector F, and for simplifying the construction, the pivot point of the guide rod D is shown in Fig. 1 as being located at the center of the clock, coinciding with the axis of the center wheel A³. 120

The shape of the slot C¹⁰ in the oscillating 125

lever arm C must be such that when the alarm hammer C⁶ is resting against the bell C¹ (as in Fig. 1) the lever C² may be rotated through the angle subtended by the slot C¹⁰. The result of so shaping and locating the slot C¹⁰ is that when the oscillating lever arm C swings to the position nearest the center of the clock, the hammer will be in contact with the bell no matter what the position of the lever C² along the slot C¹⁰. Therefore the shape of the slot C¹⁰ must be a circular arc swung from a center located at the lower end of the lever C² when the hammer C⁶ is resting against the bell C¹. But it will be understood that the arc of the slot C¹⁰ varies in relation to the center about which the lever C² turns as the link C is oscillated about the center B⁷.

In order to have the shape of the slot D¹⁵ coincide with the circular arc passed through by the pin C¹⁶ in its oscillating movement about the center B⁷, it is necessary to make the center line of this slot a circular arc swung from B⁷ as a center. Since the slot D¹⁵ is fixed in shape it is obvious that it can be made to coincide exactly with the path of the pin C¹⁶ at only one position along the oscillating lever C. In order that this may be at the position of greatest motion it is necessary that the slot D¹⁵ be fixed by swinging an arc from B⁷ as a center, with a radius equal to the length of the oscillating lever C. Thus, when the guide rod D is in the position shown in Fig. 1 the path of the oscillating pin C¹⁶ coincides exactly with the slot D¹⁵, but the path over which the said pin C¹⁶ oscillates is only a part of the total length of the slot, to wit the part from the said pin to the end of the slot nearest the free end of the rod D. The angle of oscillation of lever C is fixed by the design of the alarm escapement wheel B³ and the escapement lever B⁸ of Fig. 1. As the guide rod D swings toward the shaft B⁷ the lower or inner portion of the slot D¹⁵ is brought into use first when the guide rod is nearest B⁷, and then, as the rod swings away from B⁷ the upper part of the slot comes into use until finally, at its farthest position away from B⁷, the portion of the slot from the position of the pin C¹⁶ to the outer end thereof is the part through which the pin C¹⁶ oscillates.

The center of rotation of the guide rod D must then be fixed at the point which will make the center line of the slot D¹⁵ most nearly coincide with the various circular arcs swung by the pin C¹⁶ at its various positions along the slot C¹⁰.

The progressive movement of the lever C² outwardly along the slotted lever C is given it by the lever D which is pivoted on the central shaft A³, and is slotted at the end to receive the pin C¹⁶. Thus in its rotation it will rotate with it the lever C². The spring D¹ normally forces it and the link C² in the

direction of the shaft B⁷, and towards the silent position. The pin D⁴, however, is engaged by the spiral cam D³ which is rotated by the alarm spring, and as it rotates, forces the lever D and the lever C² to their extreme outward position along the lever C. When the rotation of the cam is completed, the pin D⁴ is released, and drops back, under the influence of the spring D¹ to that part of the cam nearest its center of rotation. The lever D and the lever C² are thereby returned to the silent position, and the cycle is then resumed. The method or rate of increase in the intensity of the alarm can be definitely controlled in the designing of the shape of the cam. The length of the complete cycle can be controlled by varying the relative length of the radii of the wheels D¹⁰ and D¹¹.

If desired, the initial intensity may be varied by moving the control sector F to the left, and thus, by the ear F¹ holding the end of the lever D, and thereby setting the lever C² along the lever C, to give the desired initial intensity to the alarm. If the control sector F is pulled to its extreme position on the left of the alarm, when set off, will start and continue at full intensity as in the ordinary alarm clock, irrespective of the rotation of the spiral cam.

Another method of varying the initial intensity is as follows. The cam D³ may be set to any desired position by means of the thumb-screw E. When the alarm is released the initial intensity of the alarm will depend on the position of the lever D which is held to the given position by the pin D⁴ bearing on the cam D³.

I provide a device for ringing the alarm intermittently which may be used either in association with the progressive variation of intensity, or may be used when the sector F is set to hold the lever C² at the position of maximum intensity. The intermittent effect is obtained through the oscillation lever G which is normally oscillated into and out of the path of the pin or stop G⁶ which controls the oscillation of the link C through its extension C¹⁵. When the lever G is in operative position, the alarm is held in silent, being released by the lifting of the intermittent lever in the course of its periodic oscillation. The intermittent feature may be disposed of by the use of the sector G⁴ which, when moved to the right, engages the end of the lever G by the pin G⁷ and holds it inoperative.

It will thus be seen that the clock may be used either as an ordinary alarm clock without the progressive acceleration of the alarm, or the accelerating feature alone may be used, or the intermittent feature, or a combination of the two, which gives a succession of increasingly intense rings.

I claim:

1. An alarm clock comprising an alarm mechanism and means for actuating it, a per-

cussion element operated thereby and means intermediate the alarm mechanism and the percussion element for increasing the impact of the percussion element on the bell, progressively from substantially no impact to a predetermined maximum impact, and means for suddenly reducing the impact to a minimum and again gradually increasing it to a maximum in a recurrent cycle.

10 2. An alarm clock comprising an alarm actuating means, a bell, a pivoted actuating lever adapted to be oscillated by said alarm, a percussion element, and an operative connection between said lever and said element, and means for varying the intensity of the alarm by moving said connection along said actuating lever.

20 3. An alarm clock comprising an alarm actuating means, a bell, a pivoted, arcuate, slotted, actuating lever adapted to be oscillated by said alarm, a percussion element and a connecting lever between said actuating lever and said percussion element a pin on the end thereof adapted to engage said slotted lever and means for varying the intensity of the alarm by moving said pin along said actuating lever, said means comprising a spiral surfaced cam rotated by said alarm actuating means.

30 4. An alarm clock comprising an alarm actuating means, a bell, a pivoted arcuate, slotted actuating lever adapted to be oscillated by said alarm, a percussion element and a connecting lever between said actuating lever and said percussion element a pin on the end thereof adapted to engage said slotted lever and means for adjusting the intensity of the alarm by moving said pin along said actuating lever, comprising a spiral surfaced cam rotated by said alarm actuating means, and a guiding rod yieldingly held in contact with said cam surface and adapted to engage and move said pin.

40 5. An alarm clock comprising an alarm mechanism and means for actuating it, a percussion element operated thereby, a bell and means for gradually increasing the range of travel of the percussion element from a predetermined minimum to a predetermined maximum, and means for setting said minimum at any point from zero to maximum.

50 6. An alarm clock comprising an alarm actuating mechanism, a bell, and a percussion element, a pivoted lever adapted to be oscillated by the alarm actuating means, a connection member between said lever and said percussion element, yielding means adapted to reduce the effective length and oscillation of said lever by forcing said member toward the pivot point of said lever, and means for progressively increasing the effective length and oscillation of said lever by advancing said member outwardly along said lever, away from its pivot point.

60 7. An alarm clock comprising an alarm

actuating mechanism, a bell, and a percussion element, a pivoted lever adapted to be oscillated, by the alarm actuating means, a connection member between said lever and said percussion element, yielding means adapted to reduce the effective length and oscillation of said lever by forcing said member toward the pivot point of said lever, means for progressively increasing the effective length and oscillation of said lever by advancing said member outwardly along said lever, away from its pivot point, and adjustable means for limiting the minimum effective length of the lever.

70 8. An alarm clock comprising an alarm actuating mechanism, a bell, and a percussion element, a pivoted lever adapted to be oscillated by the alarm actuating means, a connection member between said lever and said percussion element, yielding means adapted to reduce the effective length and oscillation of said lever by forcing said member toward the pivot point of said lever, means for progressively increasing the effective length and oscillation of said lever by advancing said member outwardly along said lever, away from its pivot point and adjustable means for limiting the minimum effective length of the lever by limiting the travel of the connecting member toward the pivot point of the lever, said adjustable means comprising a sliding sector and stop mounted on the clock frame.

80 9. An alarm clock comprising an alarm mechanism and means for actuating it, a percussion element intermittently operated thereby, a bell and means for controlling the impact of the percussion element on the bell by varying the length of the striking oscillation of said element gradually and progressively from no oscillation to maximum oscillation and abruptly back to no oscillation and thence repeatedly through the same cycle.

90 10. An alarm clock comprising an alarm mechanism and means for actuating it, a percussion element positively driven thereby and means intermediate the alarm mechanism and the percussion element for increasing and diminishing the impact of the percussion element in a continuous cycle.

100 11. An alarm clock comprising an alarm mechanism and a percussion element positively driven thereby, and means intermediate the alarm mechanism and the percussion element for varying its operative impact.

110 12. An alarm clock comprising an alarm mechanism and a percussion element positively driven thereby, a bell and means intermediate the alarm mechanism and the percussion element for varying the range of travel of the percussion element.

120 13. An alarm clock comprising an alarm mechanism and a percussion element positively driven thereby, a bell and means intermediate the alarm mechanism and the per-

cussion element for gradually increasing the range of travel of the percussion element.

14. An alarm clock comprising a percussion element, a bell, a primary actuating element, a power transmitting lever and an adjustable connection between said lever and said actuating element, and a spiral cam adapted to adjust said connection.

15. An alarm clock comprising an alarm actuating mechanism, a bell and a percussion element, a pivoted lever adapted to be oscillated by the alarm actuating means, a link connecting said percussion element with said lever, a pivoted guide rod adapted to engage

said link, yielding means adapted to force said guide rod and link toward the pivot of said actuating lever, a spiral cam rotated by the alarm actuating mechanism and adapted to engage said guide rod and to move it and said link against said yielding means and toward the outer end of said slotted lever, and adjustable means for limiting the travel of the guide rod and link toward the pivot point of the lever comprising a sliding sector and stop mounted on the clock frame.

Signed at Columbus, county of Franklin and State of Ohio, this 25th day of July, 1922.

RAYMOND C. PIERCE.
